14 Claims. (Cl. 49—220)

ABSTRACT OF THE DISCLOSURE

This application discloses an operating mechanism for a plug type railroad car door having a pair of rotatable pipes secured to the door with cranks on the ends of the pipes for moving the door laterally into and out of closed position. The operating mechanism includes a shaft rotatably supported on the door with transmission means operatively connected to the shaft so that rotation of the shaft results in rotation of the pipes and associated cranks. A brake on the shaft restrains rotation of the shaft due to forces exerted against the inside of the door by lading within the car or by compression forces of a door gasket during the major portion of the rotation of the pipes in at least the opening direction.

This application is directed to railway car doors and more particularly to an operating mechanism whereby the door may be actuated to expose the door opening.

The conventional railway plug door is adapted to be received in a door opening with the door being movable, in sequence, both laterally and longitudinally of the car. Gaskets are ordinarily provided around the periphery of the door and are adapted to be compressed against the frame of the door opening thereby to seal the opening. These gaskets are of a relatively rigid material which requires a substantial force to compress the gasket. The usual operating mechanism for such doors has comprised levers secured to the rotatable pipes mounting the door on the railway car, with the levers providing means by which sufficient mechanical advantage could be obtained to effect the compression of the gaskets as the door is closed in the opening. However, the use of such levers for operating the door has certain disadvantages particularly where the car is used for the transportation of grain and space limitations at the grain terminals preclude the use of the normal lever actuated plug door.

It is an object of this invention to provide an operating mechanism for a door in which sufficient mechanical advantage to compress the gasket is obtained without the use of levers.

It is a further object of this invention to provide a leverless operating mechanism for a railway car plug door which employs a gear and cam mechanism for actuating the pipes and locking bolts on the door.

It is another object of this invention to provide a leverless operating mechanism for a railway car door in which a brake is employed to prevent back spin of the operating handle.

More specifically, this invention contemplates an operating mechanism for a railroad car door comprising a pair of rotatable pipes secured to the door, a shaft rotatably mounted on the door and an operating lever secured to one end of the shaft. A drive gear is carried by said shaft and a gear train in meshing engagement with said gear is employed to actuate cam means rotatably mounted on the door. The cam means includes rod means interconnecting the pipes with the cam means whereby rotation of the operating lever imparts a corresponding rotation through the gear train cam means to the pipes. A brake mecha-

2

nism is supported on the shaft with the brake including a friction element effective in one direction of rotation of the shaft to restrain rotation of the shaft relative to the door.

Other objects and features will become more apparent upon a complete reading of the following description and perusal of the drawings.

In the drawings:

FIG. 1 is a front elevational view showing the invention as it is incorporated in a railway car door;

FIG. 2 is a side elevational view taken along line 2—2 of FIG. 1;

FIG. 3 is a view taken along line 3—3 of FIG. 2;

FIG. 4 is a view taken along line 4—4 of FIG. 3;

FIG. 5 is a front elevational view of the clutch of FIG. 4;

FIG. 6 is a front elevational view showing a modification of the invention;

FIG. 7 is a front elevational view showing a further modification of the invention;

FIG. 8 is a view taken along line 8—8 of FIG. 7.

Referring to FIG. 1, there is illustrated the invention as it is incorporated in a railway car plug door. The numeral 10 designates one side wall of a conventional railroad car 25 with a door opening 11 formed in the side wall. A laterally movable plug door, generally indicated by the reference numeral 12, is adapted to be received in the door opening. The precise construction of the door may vary but, in general, the door includes metal sheathing 13 and peripheral sealing gaskets 14 which are adapted to be compressed against the edges of the door opening to provide a seal when the door is closed.

To move the door laterally out of the door opening, there are provided spaced apart parallel vertical pipes 15, 35 16 rotatably secured on the exterior of the door by appropriate brackets 17. Secured to the upper end of the pipes 15, 16 are cranks 18, 19 which extend upwardly behind the top door retainer 20. The cranks are provided with rollers 21 which guide the door in its longitudinal movement and retain the top of the door in the proper position relative to the car. The pipes 15, 16 also include lower cranks 22, 23 which are journaled in roller hangers 24 slidably received upon a track 25 thereby to facilitate the sliding movement of the door longitudinally of the car.

As is well understood in the art, rotation of the pipes 15, 16 will cause a corresponding rotation of the cranks 18, 19, 22, 23 to withdraw the door laterally from the door opening. An operating mechanism, indicated generally by the reference numeral 27, is provided for controlling the rotation of the pipes and cranks. The mechanism includes a shaft 28 which is rotatably supported between a base plate 29 on the door and a cover plate 30. A handle 31 is secured to one end 32 of the shaft 28. The mechanism also employs a gear train which includes a pinion 33 secured to the shaft 28 for rotation therewith. The pinion meshes with a gear 34 secured to a shaft 35. The shaft 35, like the shaft 28, is rotatably journaled on the base plate 29 and the cover plate 30. A second pinion 36 is secured to the shaft 35 adjacent the gear 34 and is in meshing engagement with a gear segment 37. The gear segment 37 is rotatably supported on a shaft 38 with gear teeth formed only over a portion of the segment 37.

Links 39, 40 are pivotally connected at 41, 42 to the gear segment 37. The links 39, 40 are pivotally connected to the end of connecting rods 43, 44 respectively. A crosshead arrangement including a pair of slide guides 45 permits pivoting movement of links 39, 40 relative to rods 43, 44 and also provides a guide support for reciprocation of rods 43, 44. Each of the connecting rods 45 is pivotally connected to a clevis 48 secured to the pipes 15, 16 whereby sliding movement of the connecting rods

43, 44 will impart a rotating movement to the pipes and cranks.

The gear segment 37 includes an arcuate cam surface 50 with the cam surface including a substantially radial terminal shoulder 51 at one end and a cam recess 52 at the other end. A cam follower 53 is pivotally supported on pin 54 for pivotal movement toward and away from the gear segment 37. A roller 55 is carried by the follower with the roller being adapted to follow the cam surfaces 50, 51, 52. The cam follower further includes a pin 56 pivotally interconnecting the follower with a vertical link 57. The vertical link 57 includes a cam slot 58 in which are received the nose portions 59, 60 of cam followers 61, 62 respectively. The cam followers 61, 62 are pivotally supported between the base plate and the cover plate and are also pivotally connected to the ends of locking bolts 63, 64. The locking bolts are supported for longitudinal movement and are adapted to be engaged with keepers 65 on the side wall of the railway car thereby to secure the door in the door opening.

In addition to the above described combination of elements, there is included a brake mechanism which is illustrated in FIGS. 4 and 5 and comprises a hub 70 rotatably supported on the shaft 28. The hub supports a friction disc 71 which is interposed between opposed faces of a backing plate 72 and a pressure plate 73. The backing plate is interconnected at 74 with the base plate 29. Spring biasing means 75 normally clamps the friction disc 71 between the pressure plate and the backing plate.

The shaft 28 is selectively coupled with the brake by a one way roller clutch. This clutch comprises a plurality of recesses 76 formed in the interior periphery of the hub 70. These recesses each include a radially inwardly converging cam surface 77. Disposed in each recess is a wedging roller 78 with the roller having a diameter less than the maximum radial dimension of the recess 76 but greater than the minimum radial dimension of the recess. A spring 79 is also disposed in each of the recesses 76 with the spring acting against the roller 78 to bias the rollers toward the converging end of the recess 76.

As will be appreciated, as the shaft 28 turns in a counterclockwise direction, as viewed in FIGS. 1 and 5, the rollers 78 will tend to be wedged between the converging surface 77 and the exterior surface of the shaft 28 thereby coupling the shaft to the hub 70 and rendering the brake effective to restrain rotation of the shaft 28. Rotation of the shaft 28 in the opposite direction will displace the rollers 78 to a nonwedging position and the shaft 28 will rotate free of the braking action of the brake.

The above described mechanism is operated as follows: With the railroad car spotted, the plug door is opened by rotating the handle in a counterclockwise direction. The rotation of the handle transmits rotation through the gear train 33, 34, 36, 37, links 39, 40 and connecting rods 43, 44 to the pipes 15, 16 and the cranks associated therewith. Rotation of the pipes causes a lateral withdrawal of the door from the door opening. Simultaneously, rotation of the gear segment 37 causes the cam follower roller 55 to be displaced from the recess 52 which imparts a clockwise pivoting movement of the follower 53 about the pivot 54. As the follower 53 is pivoted, the vertical link 57 is displaced vertically which, through coaction of the followers 59, 60 and the cam slot 58, imparts a clockwise pivoting movement to follower 61 and a counterclockwise pivoting movement to follower 62. As the followers 61, 62 are pivoted, the locking bolts 63, 64 are retracted from locking engagement with their keepers 65 thereby releasing the door.

Lading such as grain will exert pressure against the door which will be transmitted through the cranks 18, 19, 22, 23 to the lever 31 tending to make the lever

spin out of control of the operator. However, the rollers 78 operatively connect the shaft 28 to the hub 70 in the counterclockwise direction of rotation of the shaft 28 and brake disc 71 imposes a drag which dissipates the effect of the lading and prevents spinning of the lever 31. The brake is also effective to prevent any back spin of lever 31 which may tend to occur as gaskets 14 expand from a compressed state when the door is opened. It should be noted that the drag imposed by the brake mechanism is not sufficiently great to impose any difficulty in rotating lever 31 to open the door and the brake is wholly ineffective during closing of the door.

A modification is illustrated in FIG. 6 wherein like reference numerals have been used to indicate the like parts. The segmental gear 37' shown in FIG. 7 is substantially the same as the segmental gear 37 in the embodiment of FIG. 1. However, a cam slot 50' is employed which accomplishes the same function as the cam surface 50.

In addition to the side locking bolts 63, 64 there is also included a bottom locking bolt 81. The bottom locking bolt 81 is actuated simultaneously with the side locking bolts 63, 64 through a link 82 which is connected at one end to the locking bolt 81 and at the other end to the pin 56 interconnecting the follower 53 with the vertical link 57.

The embodiment of FIG. 6 further includes a modified brake arrangement. In lieu of a friction disc there is a bracket 83 supported on the base plate. Secured to the bracket is one end of a flexible friction strap or band 84 which is adapted to encircle a portion of the shaft 28. The other end of the band includes a bolt 85 which extends through an aperture in the bracket 83 with a nut 86 threaded over the bolt retaining a spring 87 between the nut and the bracket 83. The spring 87 supplies tension to the strap 84 and tends to engage the strap with the surface of the shaft. It will be appreciated that as the shaft is rotated in a clockwise direction, as viewed in FIG. 6, the drag imparted to the shaft by the band will be minimized and will be in opposition to spring 87. However, as the shaft is rotated in a counterclockwise direction as viewed in FIG. 6, the frictional engagement between band 84 and shaft 28 will supplement spring 87 resulting in a braking action.

A further modification is illustrated in FIG. 7 wherein side locking bolts actuated from the follower 53 have been deleted and the bolts are actuated directly from the pipes 15, 16. In this construction, the side locking bolts 90 pass through guides 91 supported on the door, and may be directly connected by a link to the clevises 92 on the pipes 15, 16. However, in operating doors against which a grain load is bearing, a substantial load is imposed on each of the locking bolts. When a plurality of locking bolts are employed, a substantial force is required to withdraw the bolts to unlock the door. Moreover, it is necessary that the bolts have a limited travel due to the configuration of the bolt and the door edge and also that the operation of the bolt take place early in the cycle of the withdrawal operation of the door. Accordingly, the mechanism shown in FIGS. 7 and 8 has been devised to accomplish a rapid withdrawal of the locking bolts under the full power output of the door operating mechanism. Specifically, this mechanism comprises a generally U-shaped bracket 95 which is carried on the door adjacent to the guide 91 for the locking bolts. The bracket includes a slot 96 in each leg of the U-shaped bracket. A link 97 is pivotally connected at one end to the clevis 92 on the pipe. A force multiplying link 98 is pivoted by a pin 99 on the bracket 95 between the two legs thereof. A slot 100 is formed in the link 98 with the slotted portion of the link being received between a bifurcated portion of the link 97. A pin 101 is carried by the bifurcated portion of link 97 with the pin 101 being received in the slot 100 in the multiplying link 98 and the slots 96 in the arms of the bracket 95.

The locking bolt is pinned to the multiplying link 98.

From an inspection of FIG. 8, it is apparent that as the pipe 15 is rotated in a clockwise direction, the link 97 will be displaced so that the pin 101 traverses the slot 96. Due to the engagement of the pin 101 in the slot 100, the multiplying link 98 will also be pivoted about the pin 99 causing a retraction of the locking bolt. Since the bolt is actuated directly from the pipe 15, there is a minimum of power loss and, due to the force multiplying effect of the link 98, a rapid retraction of the bolt is obtained.

It is to be readily appreciated that many modifications of the above-described mechanism and modifications may be made. For example, the brake of the embodiment of FIG. 1 may be used with any of the other embodiments herein described. So also, the band brake illustrated in the embodiment of FIG. 6 may be employed with any of the other embodiments. Moreover, the side locking bolts and the bottom lock bolts of the various embodiments may be interchanged so that any desired combination of side lock bolts and actuating mechanism may be employed to perform the intended function.

We claim:

1. In a railway car door, the combination comprising: a pair of rotatable pipes secured to the door; 15 crank means on either end of each of said pipes with said crank means being adapted to be supported on the side of a railway car; an operating mechanism for rotating said pipes; said operating mechanism comprising a shaft rotatably supported on the door; a lever secured to one end of said shaft; transmission means supported on said door interconnecting said shaft with said pipes whereby rotation of said shaft imparts corresponding rotation to said pipes; and 35 brake means on said shaft operable in response to forces exerted against the inside of the door to restrain rotation of said shaft during the rotation of the pipes in at least one direction.
2. The combination of claim 1 wherein said transmission means comprises a gear train including a pinion secured to said shaft; gear means in meshing engagement with said pinion; a gear rotatably supported on said door and in meshing engagement with said gear means; and 45 linkage means interconnecting said gear with each of said pipes.
3. The combination of claim 2 wherein each of said linkage means comprises a link pivotally connected to 50 said gear; a connecting rod connected at one end to one of said pipes; and means pivotally interconnecting said link and rod.
4. The combination of claim 1 and including locking bolts slidably supported on said door; and 55 means interconnecting said bolts with said operating mechanism.
5. The combination of claim 4 wherein said bolt connecting means comprises: 60 a rotatable cam supported on said door; a cam follower in engagement with said cam; a link movably connected to said follower; and motion transmitting means interconnecting said link with said lock bolts.
6. The combination of claim 4 wherein said locking bolts includes a vertically movable bottom locking bolt; said connecting means further including a link secured to said movable link at one end thereof and to said bottom locking bolt at the other end thereof whereby reciprocation of said movable link imparts a corresponding reciprocation to said bottom locking member.
7. In a railway car door, the combination comprising: 70 a pair of rotatable pipes secured to the door;

crank means on either end of each of said pipes with said crank means being adapted to be supported on the side of a railway car; an operating mechanism for rotating said pipes; said operating mechanism comprising a shaft rotatably supported on the door; a lever secured to one end of said shaft; a pinion secured to said shaft; a first gear rotatably supported on said door in meshing engagement with said pinion; a second gear coaxial with said first gear and secured for rotation therewith; gear means rotatably supported on said door in meshing engagement with said second gear; linkage means connected to each of said pipes; and means connecting said linkage means with said gear means whereby rotation of said gear means imparts reciprocation to said linkage means.

8. The combination of claim 7 wherein the linkage means for each of said pipes comprises: 20 a connecting rod connected at one end to one of said pipes; a link pivotally connected at one end to said gear means; means pivotally interconnecting the other ends of said link and said rod; a slide guide fixedly secured to said door; said pivotal interconnection of said link and said rod being received in said slide guide; and means on said other end of said rod in sliding engagement with said guide.
9. In a railway car door, the combination comprising: a pair of rotatable pipes secured to the door; 25 crank means on either end of each of said pipes with said crank means being adapted to be supported on the side of a railway car; operating means on said door connected to said pipes for rotating the same; locking bolts slidably supported on said door; and means interconnecting each of said bolts with one of said pipes; said interconnecting means comprising a clevis secured to one of said pipes; a link pivotally connected to said clevis; a bracket fixedly secured to said door; a slot formed in said bracket; a multiplying link pivoted on said bracket; a slot formed in said multiplying link; 35 at least a portion of said slot in said multiplying link being in overlapping alignment with said slot in said bracket; said locking bolt being connected to said multiplying link; and pin means carried by said first mentioned link; said pin means being disposed in said aligned slots in said bracket and said multiplying link.
10. In a railway car door, the combination comprising: 40 a pair of rotatable pipes secured to the door; crank means on either end of each of said pipes with said crank means being adapted to be supported on the side of a railway car; an operating mechanism for rotating said pipes; said operating mechanism comprising a shaft rotatably supported on the door; a lever secured to one end of said shaft; transmission means supported on said door interconnecting said shaft with said pipes whereby rotation of said shaft imparts corresponding rotation to said pipes; 45 brake means on said shaft operable to restrain rotation of said shaft in at least one direction of rotation thereof; said brake means comprising a hub rotatably received over said shaft; said hub including a plurality of circumferentially

spaced recesses formed in the inner periphery thereof; wedging means in said recesses; each of said recesses including a cam surface converging radially inward toward the periphery of said shaft; the maximum height of said wedging means being less than the maximum radial depth of said recesses and greater than the minimum radial depth of said recesses; a friction disc carried by said hub; a friction surface fixedly secured to said door; and means biasing said friction disc into frictional engagement with said surface.

11. In a railway car door, the combination comprising: a pair of rotatable pipes secured to the door; crank means on either end of each of said pipes with said crank means being adapted to be supported on the side of a railway car; an operating mechanism for rotating said pipes; said operating mechanism comprising a shaft rotatably supported on the door; a lever secured to one end of said shaft; transmission means supported on said door interconnecting said shaft with said pipes whereby rotation of said shaft imparts corresponding rotation of said pipes; brake means on said shaft operable to restrain rotation of said shaft in at least one direction of rotation thereof; locking bolts slidably supported on said door; connecting means interconnecting said bolts with said operating mechanism; said connecting means including a clevis secured to at least one of said pipes; a link pivotally connected to said clevis; a bracket secured to said door; a slot formed in said bracket; a multiplying link pivoted on said bracket; a slot formed in said multiplying link; at least a portion of said slot in said multiplying link being in overlapping alignment with said slot in said bracket; said locking bolts being connected to said multiplying link; and pin means carried by said first-mentioned link; said pin means being disposed in said aligned slots in said bracket and said multiplying link.

12. In a railway car door, the combination comprising: a pair of rotatable pipes secured to the door; crank means on either end of each of said pipes with said crank means being adapted to be supported on the side of a railway car; an operating mechanism for rotating said pipes; said operating mechanism comprising a shaft rotatably supported on the door; a lever secured to one end of said shaft; transmission means supported on said door interconnecting said shaft with said pipes whereby rotation of said shaft imparts corresponding rotation to said pipes; brake means on said shaft operable to restrain rotation of said shaft in at least one direction of rotation thereof;

said brake means comprising a bracket secured to said door adjacent said shaft; a friction strap secured at one end to said bracket and encircling a portion of said shaft; and biasing means in engagement with the other end of said strap and biasing said strap into engagement with said shaft.

13. In a railway car door, the combination comprising: a pair of rotatable pipes secured to the door; crank means on either end of each of said pipes with said crank means being adapted to be supported on the side of a railway car; an operating mechanism for rotating said pipes; said operating mechanism comprising a shaft rotatably supported on the door; locking bolts slidably supported on said door; means interconnecting said bolts with said operating mechanism; a lever secured to one end of said shaft; transmission means supported on said door interconnecting said shaft with said pipes whereby rotation of said shaft imparts corresponding rotation to said pipes; said transmission means comprising a pinion secured to said shaft; a first gear rotatably supported on said door in meshing engagement with said pinion; a second gear coaxial with said first gear and secured for rotation therewith; gear means rotatably supported on said door in meshing engagement with said second gear; linkage means connected to said pipes; means connecting said linkage means with said gear means whereby rotation of said gear means imparts reciprocation to said linkage means; and brake means on said shaft operable to restrain rotation of said shaft in at least one direction of rotation thereof.

14. The combination of claim 13 wherein said brake means comprises: a hub rotatably received over said shaft; said hub including a plurality of circumferentially spaced recesses formed in the inner periphery thereof; wedging means in said recesses; each of said recesses including a cam surface converging radially inward toward the periphery of said shaft; the maximum height of said wedging means being less than the maximum radial depth of said recesses and greater than the minimum radial depth of said recesses; a friction disc carried by said hub; a friction surface fixedly secured to said door; and means biasing said friction disc into frictional engagement with said surface.
